UNITED STATES PATENT OFFICE.

JOSEPH E. YOUNG AND ERNEST V. YOUNG, OF NEW YORK, N. Y.

CONDIMENT-HOLDER.

1,193,332.

Specification of Letters Patent. Patented Aug. 1, 1916.

Application filed September 2, 1915. Serial No. 48,649.

To all whom it may concern:

Be it known that we, JOSEPH E. YOUNG and ERNEST V. YOUNG, citizens of the United States, and residents of the city of New York, borough of Brooklyn, in the county of Kings and State of New York, have invented a new and Improved Condiment-Holder, of which the following is a full, clear, and exact description.

10 Our invention relates to a double-chamber condiment holder, from either of which chambers an ingredient can be dispensed without discharging from the other chamber.

15 The object of the invention is to provide a simple, strong and inexpensive condiment holder having two independent concentric chambers refillable from opposite ends.

With the above and other objects in view, 20 the nature of which will more fully appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is an elevation of our condiment 30 holder; Fig. 2 is a vertical section therethrough; Fig. 3 is a plan view, a portion of the top of the condiment holder being broken away to show the details of construction; Fig. 4 is a similar view showing the means 35 controlling the outlet of the chambers in a different position; and Fig. 5 is an enlarged plan view on the top of the holder, partly in section to show the details of construction.

Referring to the drawings, the outer container 6 is preferably formed of two metal 40 sections 7 and 8. The upper section 7 is frustocone shape and engages the lower section 8 with its larger end by rolling the end 9 of the section 7 against flange 10 of the section 8. The flange 10 is bent outwardly 45 from the edge of the section 8, which is preferably a portion of a sphere having an extended collar 11 undulated to form a thread and co-axial with the section 7. The 50 collar 11 forms the opening through which the container 6 can be filled. A plug 12 is threaded into the collar and forms the base of the holder. The upper, smaller end of the section 7 is enlarged to form an aper- 55 tured head 13, the top of which slopes.

An inner container 14 is suspended within

the outer container from the top by means of a sleeve 15, the lower edge 16 of which projects through the apertured head 13 and is rolled to engage the inwardly directed 60 edge of the upper section 17 of the inner container and maintain the same against the top of the head 13 of the outer container. The upper section 17 of the inner container is also frustocone shape, and its larger end 65 18 is rolled against the flange 19 of the lower semi-spherical section 20. The engagement of the sleeve 15 with the head closes the outer container at the upper end, while it leaves the inner container open at the top. 70 A thimble 21 covers the projecting sleeve 15 on which it is prevented from turning by inwardly-directed indentures 22 and 23 respectively, the said indentures allowing the thimble to be pulled off or forced upon the 75 sleeve.

A perforated cover 24 is mounted on the sloping top. It has a portion 25 bent over the head, which prevents the cover from slipping off, although it is free to turn. The 80 top has a collar 26 which projects above the head 13 and which surrounds the lateral surface of the thimble 21. The collar is undulated to form a thread on to which a cap 27 can be threaded. The cap is connected to 85 the thimble by a rivet 28 which connects the two together and allows the cap to turn on the thimble, whereby when the cap is screwed on or off it carries therewith the thimble without turning the same. The 90 purpose of this is to maintain the proper relation between openings 29 in the cap and openings 30 in the thimble. The sloping top of the head 13 has also apertures 31 adapted to register with perforations 32 in the cover 95 24. The movement of the cover on the top is limited by a pin 33 secured to the head 13 and protruding through a slot 34 in the cover. The slot is so related to the openings in the head and cover and in the cap and 100 thimble that when it is in the position shown in Fig. 1 the openings 30 are in register with the openings 29; that is to say, ingredients may be dispensed from the inner container 14, but when the cover is moved to 105 the position shown in Fig. 4, the openings 30 and 29 are out of register, while the openings 31 and 32 are in register, thereby ingredients may be dispensed from the outer container and not from the inner.

In order to give a preponderance of 110 weight to the condiment holder at the bot-

tom, for maintaining the same upright, or restoring the holder to an upright position if knocked over, the base plug 12, is weighted. In the preferred form, the plug 5 has a solid core 12^a, and a threaded sheet metal shell, which is flanged over the top of the core as at 12^b, Fig. 2. Desirably a disk 12^c, on top of the weight core 12^a, is engaged and held in place by the flange 12^b 10 to constitute the bottom surface of the shell section 8 when the plug 12 is in place.

We claim:

1. A condiment holder comprising,—an outer container opening at the bottom and having an apertured top, an interior container open at the top suspended within the outer container through the aperture in the top, a plug closing the bottom of the outer container and forming the base of the holder, a perforated thimble covering the open top of the inner container, a cover having perforations fitting over the top of the outer container, said top having perforations adapted to register with the perforations of the cover, and a cap detachable from the cover and having perforations adapted to register with the perforations in the thimble, substantially as and for the purpose set forth.
2. A condiment holder comprising,—an outer container open at the bottom and having an apertured enlarged top, an interior container open at the top suspended within the outer container, a sleeve securing the top 35 of the inner container to the top of the outer container at the aperture in the top, a perforated thimble fitting on the sleeve, said thimble and sleeve having means preventing the thimble from turning on the sleeve but 40 allowing the thimble to be pulled off or forced upon the sleeve, a cover mounted to turn on the top of the outer container, said cover having a collar surrounding the thimble, a cap threaded on to the collar and secured to the thimble so that the same is 45 free to turn relative to the thimble but is prevented from axial displacement upon said thimble, and a plug for the bottom of the outer container forming a base for the

holder, said top of the outer container having perforations adapted to register with the perforations in the cover and said cap having perforations adapted to register with the perforations in the thimble.

3. A condiment holder comprising,—an outer compartment open at the bottom and having an apertured enlarged top, an interior container open at the top, a sleeve securing the top of the inner container to the top of the outer container at the aperture 60 thereof, whereby said inner container is suspended within the outer container and whereby the outer container is closed at the top, a perforated thimble fitting over the sleeve whereby the inner container is closed 65 at the top, co-operating means on the sleeve and thimble preventing the turning of the thimble on the sleeve but allowing an axial movement of the thimble upon the sleeve, a perforated cover mounted to turn on the top 70 of the outer container but prevented from axial displacement, means limiting the movement of said cover on the top of the outer container, a collar associated with said cover and surrounding the thimble, a cap 75 detachably associated with the collar but adapted to participate in the movement of the cover on the top, means securing the cap to the thimble so that the cap is free to turn on the thimble, said cap adapted to remove 80 the thimble over the sleeve when the cap is detached from the cover, said cap having perforations adapted to register with the perforations in the thimble, the top of the outer container having perforations adapt- 85 ed to register with the perforations in the cover, and a plug for the opening in the bottom of the outer container forming a base for the holder.

In testimony whereof we have signed our names to this specification in the presence of two subscribing witnesses.
